UNITED STATES PATENT OFFICE.

DAVID D. GREEN, OF MILWAUKEE, WISCONSIN.

COVER FOR WASHING-MACHINE TUBS.

1,379,014.

Specification of Letters Patent.

Patented May 24, 1921.

Application filed March 22, 1920. Serial No. 367,657.

To all whom it may concern:

Be it known that I, DAVID D. GREEN, a citizen of the United States, and resident of Milwaukee, in the county of Milwaukee and State of Wisconsin, have invented certain new and useful Improvements in Covers for Washing-Machine Tubs; and I do hereby declare that the following is a full, clear, and exact description thereof.

10 My invention relates to new and useful improvements in covers or closures for the tubs of washing-machines or like receptacles, and more particularly of that type wherein the connection of the cover member to the receptacle is effected by the provision of such interlocking relation as to avoid the necessity of providing hinges.

15 It is in general the object of my invention to simplify and otherwise improve the structure and to increase the efficiency and convenience of manipulation of closures of this character, and it is more particularly my object to provide an arrangement wherein an exceedingly strong and durable structure 20 may be procured with the use of relatively light sheet metal for the receptacle and cover, and wherein the cover may be secured in place with a binding engagement by use of a single fastening member.

25 A further object resides in the provision of a cover structure particularly adapted for use in connection with the cylindrical wall of a washing-machine tub in such manner as to prevent leakage incidental to 30 splashing of liquid within the tub.

With the above and other objects and advantages in view, which will be apparent as the description proceeds, my invention resides in the novel features of construction, 35 combination and arrangement of parts which will be hereinafter more particularly described and defined by the appended claims.

In the accompanying drawings:

40 Figure 1 is an elevational view of the upper portion of a washing-machine tub, having its top broken away, on a plane extending transversely of the axis of the tub.

45 Fig. 2 is a similar view, with the top broken away, on a plane which includes the axis of the tub.

50 Referring now more particularly to the accompanying drawing, 5 designates the cylindrical wall of a washing-machine tub 55 which is provided with the usual opening in its top, and 6 designates each of the end

walls, the mouth or opening of the cylindrical wall extending in the present instance entirely between the end walls.

In carrying out my invention, the material bounding the ends of the mouth is turned downwardly at each end to provide flanges 7 which have their extremities again turned at 8 to provide a reinforcement, and each of the flanges is inclined in the same 60 direction obliquely with respect to the vertical plane. The material of the side walls 6 is extended at the sides of the mouth opening and is bent downwardly along the inner faces of the walls and then bent inwardly 65 to form seating ledges 9 disposed slightly above the plane of the lower edges of the flanges 7. My cover member comprises the usual body portion 10 curved to afford a continuation of the cylindrical surface of 70 the wall 5 when the cover is in place, and the sides and ends of the body are bent laterally to form side and end flanges 11 and 12 respectively, the side flanges being disposed at right angles to the body of the 75 cover, to fit snugly between the inwardly turned portions of the side walls of the tub, while the end flanges 12 are inclined 80 obliquely in parallelism to correspond to the inclination of the body flanges 7 and to fit 85 thereagainst. The lower portions of the flanges 12 are bent inwardly to form reinforcements 13 holding the major portions of the flanges in rigid shape, while the lower edges of the flanges 11 are turned inwardly 90 at 14 to seat on the ledges 9 when the cover is disposed in closing position. The cover carries a suitable handle 15 and a hasp member 16 is pivoted to the end portion of 95 the body member having the lesser angle with its flange 12, said hasp member being engageable with a keeper clip 17 on the adjacent portion of the body. It is noted that the flanges 12 form differing angles with the body member by reason of their oblique 100 inclination in the same direction.

I have thus provided an exceedingly simple and efficient cover particularly adapted for washing-machine tubs, which may be effectively secured in place with the use of a 105 single fastening member, and it is noted that as the hasp carrying end of the cover is forced downwardly, a camming action will be set up between the adjacent cover and body flanges 12 and 7 respectively, causing 110 the cover to move rearwardly to procure binding engagement between the other pair

of flanges 7 and 12, and securely locking the cover in place, and preventing leakage past the cover. It is further noted that the flange members for procuring this interlocking 5 and binding action serve to materially brace the tub body and cover sheeting, and the stresses incidental to securing of the cover member in place are distributed in such uniform manner as to permit the use 10 of a maximum weight of metal at these places.

While I have described my invention as being associated with a washing-machine structure for which it is particularly adapted, it will be appreciated that my invention may be embodied in the covers for other types of receptacles, and that various changes and modifications of structure 15 may be employed to meet differing conditions of use and manufacture without departing in any manner from the spirit of my invention.

It will be noted that the flanges 12 and 11 form edge faces on the cover member engageable with corresponding faces of the body member formed by the turned marginal portions thereof.

What is claimed is:

1. The combination with a receptacle having an opening bounded by plane edge faces, the opposing faces being parallel, certain of said faces being inclined obliquely and a removable cover member having end faces engageable with the edge faces of the receptacle opening and having certain of its faces inclined obliquely to correspond to the inclination of the inclined faces of the receptacle opening, and means for securing said cover member with its outer surface flush with the outer surface of the receptacle.

2. The combination with a receptacle having an opening bounded by edge faces, opposed faces of said opening being inclined obliquely in substantially parallel relation,

a cover member having opposed faces correspondingly inclined for engagement with said inclined edge faces, said opposed end faces of the cover member forming consequently different angles with the surface of the cover member, a fastening means for the cover member at the end portion thereof having the lesser angle of its end face, and a seat for said cover member inwardly of the edge faces of the receptacle.

3. The combination with a receptacle having an opening, of the material at the edge portions of said opening being turned inwardly to provide flanges, the lower portions of opposed flanges being turned toward each other to provide seats, and a removable cover sheet having its edge portions turned laterally and connected to provide flanges fitting against the flanges of the body member, the lower edges of said flanges being turned inwardly to provide ledges adapted to rest on said seats.

4. The combination with a receptacle having an opening, of the material at the edge portions of said opening being turned inwardly to provide flanges, the lower portions of opposed flanges being turned toward each other to provide seats, a removable cover sheet having its edge portions turned laterally and connected to provide flanges fitting against the flanges of the body member, the lower edges of said flanges being turned inwardly to provide ledges adapted to rest on said seats, the opposed pairs of flanges of the receptacle body and cover sheet being obliquely inclined in substantially parallel relation, and means for securing one end portion of the cover sheet to the body member.

In testimony that I claim the foregoing I have hereunto set my hand at Milwaukee, 85 in the county of Milwaukee and State of Wisconsin.

DAVID D. GREEN
